UNITED STATES PATENT OFFICE.

HERBERT E. KEMPTON, OF FOND DU LAC, WISCONSIN, ASSIGNOR TO GIDDINGS & LEWIS MACHINE TOOL COMPANY, OF FOND DU LAC, WISCONSIN, A CORPORATION OF WISCONSIN.

WHEEL-DRESSING MECHANISM.

Application filed July 12, 1923. Serial No. 650,988.

The invention relates generally to means for dressing and truing the cutting surfaces of grinding wheels.

The primary object of the invention is to provide a light and sensitive wheel dressing mechanism which is operable to effect an accurate and precise truing of the cutting surface at considerable speed.

Another object is to provide a device of the above character which when not in use can be quickly moved into an inoperative position away from the grinding wheel, and which can be quickly and accurately returned to its operative position ready for immediate and instant use.

A further object is to provide a dressing device in the form of a single and permanent attachment which can be mounted in a convenient position upon the grinding wheel carriage, so as to be within easy reach of the operator and ready for use at all times.

Ancillary objects and advantages will be made apparent by the following description taken in connection with the accompanying drawings, wherein Figure 1 is a plan view showing a device embodying the features of my invention mounted in its operative position on a grinding wheel carriage. Fig. 2 is a side elevational view of the structure shown in Fig. 1. Fig. 3 is a sectional view taken in the plane of line 3—3 of Fig. 1. Fig. 4 is a sectional view taken in the plane of line 4—4 of Fig. 2. Fig. 5 is a sectional view taken in the plane of line 5—5 of Fig. 2. Fig. 6 is a sectional view taken in the plane of line 6—6 of Fig. 1.

Referring to the drawings, wherein I have illustrated the preferred embodiment of my invention, 10 represents a grinding element which is mounted upon a spindle 11 journaled in a casing 12 forming part of the grinding wheel carriage. Positioned adjacent to the grinding element 10 for truing the cutting surface 13, is a wheel dressing mechanism 14 which is pivotally mounted upon the side wall 15 of the casing 12.

The wheel dressing mechanism 14 comprises a main body or supporting fitting 16 which is provided with a flange 17 fitting against a smooth vertical face 18 on the side wall 15. In the present instance, the body 16 pivotally mounted upon a stud 19 which is threaded into the wall 15, and is provided with a lug or shoulder 20 fitting tightly

against the face 18. A bore 21 formed in the flange 17 fits over the shoulder 20, and a coil spring 22 positioned on the stud 19 and abutting against the inner end of a bore 23 formed in the outer side of the body 16, serves to hold the latter firmly against the face 18 at all times. The lower edge 24 of the flange 17 is curved or circular in form, and is formed at opposite sides with lugs 25 adapted to selectively engage a stop pin 26 for different positions of the body member 16. The lugs 25 are sufficiently spaced from each other so that the wheel dressing device will be held in either of its extreme positions by its own weight. A lever 27 threaded onto the outer end of the stud 19 is adapted to lock the body 16 in any adjusted position.

The body 16 is formed with an elongated bushing 28 which supports and guides a reciprocable sleeve 29. To limit its extent of reciprocation, the sleeve 29 is provided with an integral head 30 at its forward end and is threaded at its opposite end to retain a nut 31. Relative rotation of the bushing and sleeve is prevented by an elongated key member 32 which is secured to the latter and engages a keyway 33 on the inner surface of the former. Cylindrical guards or shields 34 secured to the head 30 and nut 31 telescope with the ends of the bushing 28, and protect the bearing surfaces from dust and other foreign material.

Means is provided for manually reciprocating the sleeve 29. Supported by the stud 19 between the head 16 and the locking lever 27 is a bushing 35 upon which is pivotally mounted a hand lever 36. Movements of the lever 36 are transmitted to the sleeve 29 through a link 37, the ends of which are attached, as by pins 38, to the lever 36 and head 30, respectively.

A rod 39 extending through the sleeve 29 and supporting a dressing tool holder 40 at its outer end is rigidly clamped in any adjusted position by the head 30, which is split at 41 for a portion of its length and is provided with a clamping screw 42. The rod 39, which is preferably made of steel tubing, extends through and is rigidly secured to a lug 43 formed integrally with 100 and on the upper side of a holder casing 44. The forward end of the casing 44 is split at 45, and is provided with ears 46 through

which extends a clamping bolt 47. Slidably extending into the casing 44 is a tool rod 48, which is provided with a bore 49 at its outer end for the reception of a cutting tool 5 mounting 50. Any suitable cutting tool, as, for example, a diamond 51, may be used. The mounting 50 is held within the bore 49 by a set screw 52. The rod 48 is formed with a longitudinal groove 53 which engages 10 a pin 54 extending inwardly from the casing 44, whereby the rod and casing are feathered to prevent relative rotation.

Means is provided for effecting a relative longitudinal adjustment of the rod 48 and 15 casing 44. Mounted within the casing 44 is a diamond adjusting screw 55, one end of which extends through the rear wall 56 of the casing and to which is rigidly attached a knob 57 having a knurled gripping surface 58. A shoulder 59 on the screw 55 engages the inner surface of the wall 56 to hold the screw 55 in position. The inner end of the screw 55 is threaded, as at 60, and adjustably engages a tapped bore 61 20 in the inner end of the rod 48.

By the above construction, the diamond 51 can be fed toward and from the grinding element 10 by adjusting the knob 57, and 25 can be locked in the adjusted position by tightening the clamping bolt 47. The diamond 51 can also be fed back and forth across the grinding face 13 by oscillating the hand lever 36. The position of the holder 40 can be adjusted for spindles 11 of different lengths by adjusting the relative position of the rod 39 and the sleeve 29. When 30 not in use, the wheel dressing mechanism 14 can be swung about the stud 19 into its inoperative position and can be locked in 35 such position by tightening the lever 27. The wheel dressing mechanism 14 can be returned to its operative position without having changed a single adjustment and is 40 therefore immediately ready for use.

The mechanism is sturdy and simple in 45 construction, and accomplishes a rapid and accurate truing of the grinding wheel. Light and frequent cuts can be made because of the ease and convenience with which the 50 device can be moved into its operative and inoperative positions.

While I have illustrated the preferred embodiment of my invention with considerable particularity, it should be understood 55 that various modifications and alternative constructions may be made without departing from the spirit and scope of the invention as expressed in the appended claims.

I claim as my invention:

60 1. A wheel dressing mechanism having, in combination, a pivotal body, lugs on said body, means for engaging said lugs to limit the pivotal movement of said body, means 65 for locking said body in position, a reciprocable sleeve mounted in said body, means for

reciprocating said sleeve, a rod adjustably mounted in said sleeve, a casing supported by said rod, a tool rod mounted in said casing, a cutting tool supported by said tool rod, and means for adjusting the position 70 of said tool rod at right angles to the direction of reciprocation of said sleeve.

2. A wheel dressing mechanism, having in combination with a grinding wheel and a carriage, a body, means for pivotally mounting said body upon said carriage, a dressing tool supported by said body, means for adjusting said tool toward and from the cutting surface of said grinding wheel, means for adjusting said tool toward and from said 80 body, and means for reciprocating said tool across said cutting surface.

3. A wheel dressing mechanism having in combination with a grinding wheel and a carriage, a body, means for pivotally mounting said body upon said carriage, spaced lugs 85 on said body, means for engaging said lugs to limit the pivotal movement of said body, means for locking said body in position, a dressing tool supported by said body, means 90 for relatively adjusting said tool and said body, and means for moving said tool across the cutting face of said grinding wheel.

4. A wheel dressing mechanism having, 95 in combination with a grinding wheel and a carriage, a body pivotally mounted on a horizontal axis upon said carriage, and having an operative position in a horizontal plane and an inoperative position above said operative position, a pair of lugs on said 100 body spaced apart slightly over 90°, a projection on said carriage position between said lugs to selectively engage with said lugs to hold said body in its operative or inoperative position, a dressing tool supported by 105 said body, and means for moving said dressing tool along the face of said grinding wheel.

5. A wheel dressing mechanism having in combination with a grinding wheel and a 110 carriage, a body, a stud for pivotally mounting said body upon said carriage, means for holding said body in any one of a plurality of angular positions, a reciprocable member 115 non-rotatably mounted in said body, a dressing tool supported by said member, a lever mounted on said stud, and means connecting said lever and said member for imparting a reciprocating motion to said member and dressing tool.

6. A wheel dressing mechanism, having in combination, a support, a body mounted on said support, a sleeve mounted for reciprocation in said body, means for reciprocating said sleeve, a dressing tool supported 125 by said sleeve, and means for adjusting said tool rotatably, longitudinally and transversely of said sleeve.

7. A wheel dressing device, having, in combination, a support, a body mounted on 130

said support, a reciprocable sleeve mounted in said body, means for reciprocating said sleeve, shields supported at opposite ends of said sleeve and telescoping with said body, a dressing tool supported by said sleeve, and means for effecting a relative adjustment of said sleeve and said tool.

8. A wheel dressing mechanism having in combination, a support, a body pivotally mounted on said support, a sleeve mounted for reciprocation in said body, means for reciprocating said sleeve, a rod mounted in said sleeve, means for longitudinally and rotatably adjusting said rod, a casing mounted transversely of said rod, a tool rod in said casing, a cutting tool mounted on said tool rod, and means for longitudinally adjusting said tool rod in said casing.

9. A wheel dressing mechanism having, in combination, a support, a body mounted on

said support, a reciprocable member non-rotatably mounted in said body, a rod extending through the member and being adjustable longitudinally and rotatably, a dressing tool supported by said rod, and means for reciprocating said member.

10. A wheel dressing mechanism having, in combination, a support, a body mounted on said support, said body being capable of movement into either an operative or inoperative position, a reciprocable member supported by said body, means for reciprocating said member, protective means enclosing the bearing surfaces of said body and said member for all positions of the latter, and a dressing tool carried by said member.

In testimony whereof, I have hereunto affixed my signature.

HERBERT E. KEMPTON.

CERTIFICATE OF CORRECTION.

Patent No. 1,631,596.

Granted June 7, 1927, to

HERBERT E. KEMPTON.

It is hereby certified that error appears in the printed specification of the above numbered patent requiring correction as follows: Page 1, line 52, before the word "pivotally" insert the word "is"; page 2, line 102, claim 4, for the word "position" read "positioned"; and that the said Letters Patent should be read with these corrections therein that the same may conform to the record of the case in the Patent Office.

Signed and sealed this 28th day of June, A. D. 1927.

Seal.

M. J. MOORE.
Acting Commissioner of Patents.
